UNITED STATES PATENT OFFICE.

EDMUND S. CHURCH, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,134,183.

Specification of Letters Patent.

Patented Apr. 6, 1915.

Application filed March 30, 1908. Serial No. 424,141.

To all whom it may concern:

Be it known that I, EDMUND S. CHURCH, a citizen of the United States, residing at Dayton, in the county of Montgomery and State of Ohio, have invented certain new and useful Improvements in Cash-Registers, of which I declare the following to be a full, clear, and exact description.

This invention relates to cash registers. 10 Among its objects is to provide a flexible but permanent connection between the keyboard or manually operated parts and the actuating mechanism for the totalizing, printing and indicating mechanisms, that is, a connection in which parts operated by the keyboard do not act as stops for the actuating mechanism but serve to regulate the extent of movement of the actuating mechanism when the driving mechanism is operated and thereby eliminate the jar and the noise caused by impact between the actuating mechanism and the spaced stops which are usually employed for regulating the movement of the same.

25 Another object is the provision of a cash register in which the type of manipulative devices (levers or keys, etc.) which control the operation of the machine may be varied as desired without also requiring some other alteration in the machine.

Another object is to provide the type of machine shown in the drawings, with means for positioning the setting elements by the main operating mechanism instead of directly from the keyboard, the keyboard in this case serving to control the operating mechanism.

Another object is to provide this type of machine with indicator mechanism which may be set to any desired position by power applied at the main drive shaft and also to retain the feature of changing the indicator mechanism from one reading directly to any other without first returning it to some normal or zero position.

45 A further object is to provide the machine with an improved automatically operated paper feeding device which is arranged conveniently for the operator to autographically record notes regarding each transaction.

With these and incidental objects, in view the invention consists in certain novel features of construction and combinations of 55 parts, the essential elements of which are set forth in appended claims and a pre-

ferred form of embodiment of which is hereinafter described with reference to the drawings which accompany and form part of the specification.

Of said drawings, Figure 1 is a transverse vertical section of a cash register constructed according to this invention. Fig. 2 is a detail of the mechanism which effects the setting of the totalizer-actuating racks. Fig. 3 is a detail of an alining device for the mechanism under control of the keyboard and also shows the key detent and mechanism for operating the same. Fig. 4 is a detail of cams mounted on the main drive shaft which control movement of the totalizer irame. Fig. 5 is a detail of a device used for returning the mechanism operated by the manipulative devices to zero position at the end of each operation of the machine. Fig. 6 is a top plan of the paper feeding device. Fig. 7 is a top plan of the same but with the cover removed. Fig. 8 is a side elevation of the same.

This invention is shown as applied to a machine which is quite extensively used at present and is fully described in the patent to Thomas Carroll No. 751,611 of February 9, 1904. The said patent describes a machine in which manipulative levers serve to shift racks so as to differently rotate the indicator drums and to bring different numbers of teeth on said racks into the path of the totalizer which is afterward caused to be moved down over the rack teeth a definite distance and will thus be rotated an extent which is determined by the number of teeth of each of the racks which are brought into its path. The same principle of totalizer actuating mechanism is used in the present invention except that the racks are not set directly by hand but are set by the main operating mechanism which is preferably motor driven or else manually driven by means of a crank handle which is mounted on a shaft geared to the drive shaft or directly upon the drive shaft itself. This lessens the work performed by the manipulative devices and causes said work to be performed by the main drive shaft thus permitting lighter action of the manipulative devices.

In the design of the machine, its adaptability for different classes of controlling devices has been kept in view. The controlling devices may either be depressible keys, pivoted hand operated segments, or levers.

The controlling devices effect the adjustment of an element (see 43, Fig. 1) of the driving mechanism and the driving mechanism in turn operates the actuators for the 5 accounting devices according to the adjustment of the element mentioned. The element of the driving mechanism which is adjusted to different positions by the controlling or manipulative devices is arranged 10 with respect to another element of the driving mechanism so that upon operation of the driving mechanism the first element will be caused to be returned to the position it had before being operated by the manipulative devices the return movement being communicated to the actuators for the accounting 15 devices.

Several banks of keys 10 are provided according to the number of denominations it 20 is desired to have represented upon the keyboard. Each bank of keys controls setting elements which are identical in all banks so only one bank of keys and its respective setting elements will be described. The machine 25 is so arranged that a single lever may be substituted for each bank of keys. One of said levers is shown by broken lines in Fig. 1. The keys are mounted in banks in the frame of the machine at 11 and are 30 pressible against the action of springs 12. Each key carries a pin 18 which when the key is depressed will engage one of the inclined teeth 14 of the key detent bar 15 (Fig. 3) and cam the bar downwardly until 35 the pin reaches the recess 16 in the bar when the bar will spring upwardly under the action of its spring 17 and retain the key in its depressed position. A lever 18 (Fig. 1) pivoted at 19 is arranged at the side of each 40 bank of keys in the path of the pins 13 so that when any key is depressed the pin 13 of such key will engage the lever 18 and rock the same on its pivot 19.

There are nine keys to each bank arranged 45 at successive distances from the pivotal center of the lever 18, and as the keys are all depressed a uniform distance the key which is nearest to the pivotal center of the lever 18 will rock the lever 18 the greatest distance. This is the "nine" key of the bank. The other keys will rock the lever 18 successively decreased distances up to the "one" key which is at the top of the bank. The lever 18 is connected by a link 20 through 50 intermediate mechanism to a prime actuator 21 for its respective type segment and indicator drum. The prime actuators 21, one for each bank of keys are all loosely journaled on a shaft 28 extending across the machine. 55 The actuators have two sets of rack teeth cut upon their peripheries. The sets 22 are arranged to mesh with pinions 23 which are rigidly mounted upon one end of the shaft 24 or on one of a series of sleeves 25 surrounding said shaft. The other end of the

shaft 24 and each sleeve has mounted thereon a type-carrying disk, not shown in the drawings as it is part of the printing mechanism and the printing mechanism forms no part of the present invention but was described in the patent above referred to. Mention of the printing mechanism is merely made to explain the purpose of the rack teeth 22. The pinion 23 which is rigidly mounted upon the shaft 24 is connected by 70 said shaft to the units type-carrier. The pinions which position the type carriers of higher denominations are connected to their respective type carriers by the tubes or sleeves 25 which are mounted concentric with the shaft 24. The other set of rack teeth 26 upon the actuator 21 mesh with rack teeth 27 upon a rack member 29 which is vertically movable in guides 30 and 31. The rack member 29 is furnished with two other 80 sets of rack teeth, besides the set 27, which are indicated at 32 and 33. The set 33 meshes with a pinion 34 which is rigidly secured to the side of one of the indicator drums so that any movement of the rack member 29 will cause the indicator drum 35 to be rotated accordingly. The set of 85 rack teeth 32 are the ones with which one of the totalizer pinions will mesh when the totalizer is operated so as to move downwardly over the rack.

The connection between the link 20 and the actuating segment 21 before referred to as the intermediate mechanism between said members consists of a plate 36 which is 100 loosely mounted upon the shaft 28 and to which the link 20 is pivoted, and a pair of links 37 and 38. The link 37 is pivoted to the member or plate 36 and the link 38 is pivoted to the actuating segment 21 at 39. 105 The other ends of the links 37 and 38 are joined together at 40 at which joint a roller 41 is mounted. The roller 41 extends into a curved slot 42 in a lever 43 which is pivotally mounted at 44. With this construction if the segment 21 is prevented from rocking upon its pivot 28 and the member 36 is free to rock on said pivot and if one of the keys is depressed so as to rock the member 36 the rocking of the member 36 will cause 110 the roller 41 to be moved an extent away from its zero position according to the key which is depressed. A change of position of the roller 41 will adjust the lever 43 accordingly. If the member 36 is now prevented from rocking upon its pivot 28 and the segment 21 is no longer locked against movement and if the lever 43 is returned to its original position it will also cause the roller 41 to move with it, the roller 41 being 115 free to slide within the slot 42. As at this time the member 36 is prevented from movement, the return of the roller 41 will merely cause the link 37 to rock upon its pivotal connection with the member 36 but as the 120 125 130

segment 21 is free to move, the rocking of the link 37 will, through the link 38 rock the segment 21 according to the amount of return movement of the roller 41 which movement exactly corresponds with the extent to which the roller 41 had been moved away from its zero position.

In order to rock the lever 43 it has a V-shaped recess 46 cut into its lower side 10 extending radially from the pivot 44 of the lever 43 so that the apex of the recess points toward the pivot. A roller 47 is mounted opposite the recess 46 upon the lever 48 which is rigidly mounted upon a shaft 50, 15 and also mounted upon the shaft 50 is a lever 51 connected by a pitman 52 to a cam 53. (See Fig. 2.) The pitman 52 carries a roller 154 which extends into a slot 55 in the cam 53 rigidly mounted upon the main 20 drive shaft 54 which shaft is caused to make one complete rotation at each operation of the machine. This will cause the lever 48 to be rocked once during each operation of the machine so that the roller 47 will move 25 up into the recess 46 and cause the return of the lever 43 to its initial position if the lever 43 has been moved out of such position through depression of one of the keys 10, because if the lever 46 is moved out of its 30 initial position one of the inclined edges of the recess 46 will be brought into the path of the roller 47 so that when the roller 47 is moved upwardly into the recess it will engage the inclined edge of the recess and cam 35 the lever 43 back to its zero position. The cam 53 is so arranged upon the drive shaft 54 that it will cause the lever 48 to be rocked upwardly and returned soon after the shaft 54 starts to rotate so that after the lever 48 40 has been rocked upwardly and returned the shaft 54 will still rotate far enough to effect the reciprocation of the totalizer 56 over the rack 32. Immediately after the shaft 54 starts to rotate an alining pawl 57 (see Fig. 45 3) will be locked into engagement with teeth 58 cut into the member 36 so that the member 36 will be locked into whatever position it has been moved by the depression of one of the keys 10. The alining pawl 57 is 50 rigidly mounted upon the shaft 44. A lever 59 is also mounted upon the shaft 44, and is operated through a pitman 60 by a cam 61 rigid with the drive shaft 54. A roller 62 upon the pitman 60 co-acts with the cam 61 55 so that the pitman 60 will be drawn upward immediately after the drive shaft 54 starts to rotate and held in such upward position while the lever 48 is being rocked upwardly in order to set the segment 21 and the rack 60 member 29 to a desired position. A lug 63 extends from the lever 59 in under the alining pawl 57 and will prevent the pawl 57 from rocking upon its pivot 44 when the pitman 60 is held in its upper 65 position by the cam 61. When the pit-

man is in its lower position the pawl will not prevent movement of the member 36 because then it is merely held into engagement with the member 36 by the spring 64. The cam 61 is arranged upon the shaft 54 70 so as to release the pawl 57 when the shaft 54 has made about two thirds of a revolution, the pitman remaining released from the cam 61 at the completion of an operation of the machine so as not to prevent movement of 75 the member 36 when the keys are again depressed. After the segment 21 and the rack member 29 have been shifted through the engagement of the roller 47 with the recess 46 they will be locked in such position by a 80 plunger 65 which is arranged to be moved into co-acting notches in an alining plate 66 mounted upon the side of the rack member 29. The alining plunger 65 is held into engagement with the alining plate 66 by a 85 lever 67 rigid with a shaft 68, having rigidly mounted thereon a lever 69 which carries a roller 70 co-acting with a cam 71 which is mounted upon the drive shaft 54. This cam 71 is arranged so as to lock the plunger 65 90 with the alining plate 66 at all times except when the lever 48 is being rocked upwardly which occurs when the drive shaft has made about one-ninth of a revolution.

The totalizer 56 is mounted in a frame 73 95 which frame is caused to be reciprocated in a frame 74 (see Fig. 4) at each operation of the machine after the rack members 29 have been set in desired positions and locked in such positions. The sides of the frame 73 are 100 connected by tie bars 75 which bars carry rollers 76 running in tracks 77 of the frame 74 and guide the frame 73 when the frame 73 is reciprocated. The frame 73 is caused to be reciprocated at the proper time by levers 78 one on each side thereof, (see Fig. 4) which are pivoted to the frame of the machine. The forward ends of the levers 78 are slotted, through which slots the lower tie bar 75 extends. The levers 78 are provided with rollers 79 extending into cam grooves 80 cut into cam disks 81 which are rigid with the drive shaft 54. Cams 81 operate the levers 78 so that they will draw the totalizer down over the racks 32 and then return the same once every time the drive shaft 54 makes a complete rotation. The frame 74, in which the totalizer frame 73 travels is pivotally hung from the frame of the machine at 82. (Fig. 1.) A pitman 83 110 is pivoted at 84 to the lower end of the frame 74 and is at its opposite end forked over the drive shaft 54. The pitman 83 carries a roller 85 (Fig. 4) extending into a cam groove 86 which is cut into a disk carried by the drive shaft 54. The action of the cam groove 86 upon the roller 85 will cause the frame 74 to be rocked rearwardly toward the rack 32 and held in such position when the totalizer is moved downwardly over the 115 120 125 130

rack 32. When the totalizer is in its lowest position the cam 86 will cause the frame 74 to be rocked outwardly so that the totalizer upon its return will not mesh with the rack 32.

The totalizer 56 (Fig. 1) described in the patent to Thomas Carroll, before mentioned, comprises a plurality of numbered drums 87 which each carry a pinion 88. The pinion 88 of the drum 87 of the units denomination is positioned to be meshed with the rack 32 which is controlled by the units bank of keys. The other pinions of course mesh with the racks 32 which are controlled by banks of keys of corresponding denominations. When a pinion 88 makes a complete rotation such rotation is registered upon the pinion of next higher denomination which is then caused to rotate one additional unit of movement. The transferring is effected by a pawl 89 which is pivotally mounted upon the arm 90 pivoted at 91 to the totalizer frame 73 and is adapted to engage a ratchet 92 rigid with its respective totalizer pinion but it is normally held out of engaging position with the ratchet 92 by a pivoted detent 93. The detent 93 has a projection 94 extending into the path of a pin 95 which extends from the totalizer drum or pinion of the next lower order than the one which the pawl 89 is intended to operate upon. When the totalizer frame 73 is being returned to its upper position a roller 96 which is carried by the lever 90 will engage one of the inclined surfaces 97 and will cause the lever 90 to be rocked upon its pivot 91 and so move the pawl 89 upwardly. The pawl 89 will not ordinarily engage the ratchet 92 as it will be held away from the ratchet by the detent 93 but if the totalizer pinion makes a complete revolution the pin 95 will cause the detent to be rocked downwardly upon its pivot 93 so that the extension 99 on the pawl 89 will spring into a notch cut into the detent 93 and the pawl 89 will then not be held away from the ratchet 92 upon the return of the totalizer at which time the roller 96 engages one of the inclined surfaces 97. The pawl 89 will then engage one of the teeth of the ratchet 92 and cause the ratchet to be moved forwardly one tooth space. A retaining pawl 101 prevents backward rotation of the ratchet and also of its respective totalizer pinion.

After the rack members 29 have been properly set and before the drive shaft 54 comes to rest the depressed keys are released and the levers 18 are returned to zero positions ready for another operation of the machine. The levers 18 are returned to zero positions by means of a frame 103 which extends in under all of the arms 104 of the member 36. The frame 103 is shown in Figs. 1, 3, and 5. It is operated by means of a pitman 105 which is in turn operated by

a cam 106 (Fig. 5) which cam is rigid with the drive shaft 54 and is arranged on the drive shaft 54 so that it will cause the frame 103 to be rocked upwardly and returned just before the drive shaft 54 comes to rest after an operation of the machine. In rocking upwardly the frame 103 engages all of the members 36 which have been moved out of their zero positions and returns the same to their zero positions and through the link 75 connection 20 between the members 36 and the levers 18 will cause the levers 18 also to be returned to zero positions. The frame 103 is provided with a cam surface 107 (see Fig. 3) which engages a roller 108 upon the pitman 109 when the frame is rocked upwardly. The pitman 109 is pivoted to a bell-crank lever 110 which is arranged to be rocked upon its pivot 111 when the pitman is drawn rearwardly by the cam 107. The bell-crank lever 110 engages a pin 112 extending from the side of the key detent plate 15 and causes the plate to be lowered away from any depressed key which it has held in depressed position, upon which springs 90 12 will force out any depressed keys and the machine will be left in condition to again be operated.

The operation of the machine as so far described is as follows. First, the desired amount keys 10 are depressed. The depression of any of the keys causes the levers 18 of their respective banks to be rocked a greater or less extent depending upon the distance the depressed key is from the pivotal center of the lever 18. Movement of the lever 18 will cause a corresponding movement of the member 36 upon its pivot 28 because of the link connection between the lever 18 and the member 36. Movement of the member 36 is imparted to the roller 40 through the link 37 and as the roller 40 extends into the slot 42 of the lever 43 it will also rock the lever 43 upon its pivot 44. As the segment gear 21 is locked against movement at this time by the alining plunger 65 the shifting of the roller 40 cannot cause movement of the segment but will merely rock the lever 38, which connects it to the segment, upon its pivot 39. The drive shaft 105 is now caused to make a complete rotation. As soon as the drive shaft starts to rotate it will cause the alining plunger 57 to lock the member 36 against movement and it will also bring the cut away part of the cam 71 opposite the roller 70 on the lever 69 and so no longer hold the locking plunger 65 into engagement with the alining plate 66 so that the rack member 29 and the segment gear 21 will now be free to be operated. As soon as the segment gear 21 and rack member 29 are released the lever 48 is rocked upwardly by means of the pitman 52 so that the roller 47 will move up into the V-shaped recess 46 and cause the lever 43 130

to be cammed back to its original position. As the member 36 is now locked against movement and the segment gear 21 is unlocked the return movement of the lever 43 operating upon the roller 40 will cause the segment gear to be moved to a position which corresponds in distance from its zero position to the distance which the lever 18 had been moved away from its zero position.

If at the end of an operation of the machine the rack 29 is left in a higher position than the amount of the key of its respective bank which is depressed, upon the next operation of the machine, the lever 43 will operate to lower the rack member 29 to the correct position exactly as it would raise the rack if the rack had been left in its zero position except that the roller 47 will engage the opposite surface of the recess 46. The sole function of the lever 43 is to restore the angle between the links 37 and 38 to that which must be maintained in order to have the position of the rack member 29 and the lever 18 correspond. Fig. 1 shows the rack member 29 and the lever 18 both in their zero positions and the links 37 and 38 are shown substantially at right angles and would be at right angles to one another whenever the position of the rack member 29 and the lever 18 correspond. If the lever 18 is rocked away from its zero position and the rack member 29 is locked against movement, the roller 40 will be moved farther away from the center of the shaft 28 and the angle between the links 37 and 38 will become more acute. Under these conditions if the lever 18 is locked in its moved position and the rack member 29 released, by returning the roller 40 to its original distance from the center of the shaft 28, the links 37 and 38 will again assume their original angular relation and in doing so will effect the positioning of the rack member 29 to correspondence with the position of the lever 18.

As the pinion 23 meshes with the teeth 22 of the segment gear the said pinion will cause the positioning of its respective type-carrier accordingly. The rack teeth 26 of the segment gear 21 will properly position the rack member 29 so that the indicator drum 35 will be correctly set and also the correct number of the rack teeth 32 will be moved up into the path of the totalizer. The cam 71 will now cause the alining plunger 65 to lock the rack member 29 in its set position. The totalizer is now swung inwardly and brought down over the racks 32 so as to be forwardly rotated the desired amount and is then rocked out of engagement with the racks 32 and returned to its upper position. Any necessary transferring operation of the totalizer is effected during the return movement of the totalizer

frame. The cam members 97 which operate the transfer devices are successively arranged so that no transfer will be lost through the simultaneous operation of several of the transfer pawls 89.

It will be seen from Fig. 1, how, that depressed keys will co-act with the levers 18 so that the pins of the keys will prevent overthrow of the lever 18, the pin engaging one of the notches 155 of the lever 18 when the key has reached the limit of its inward movement.

The release of the keys from detents 15 is effected just before the levers 18 are returned to their zero positions.

In Fig. 1 a modified form of the manipulative device is shown in the form of a lever 113 which is shown in broken lines as riveted to the member 36. If the lever is moved downwardly from the position shown, an extent equal to that between any two of the keys it will cause the member 36 to be moved to any of the positions to which it may be moved by the depression of any one of the keys. As the lever 113 controls the positioning of the member 36 exactly as does a bank of keys, the substitution of a lever for a bank of keys will necessitate no other alteration of the machine. This is also the case when the hand operated segment is substituted for the bank of keys.

The usual cash drawer is shown in broken lines in Fig. 8 at 114. The mechanism for opening the cash drawer is not illustrated in the drawings but was fully described in the patent to Carroll before mentioned. An autographic recorder is placed within the drawer and is provided with a bell-crank lever 115 which extends upwardly so as to be engaged by a lug 116 extending from the base plate of the machine when the cash drawer is returned to its closed position. The bell-crank lever 115 is rigidly mounted upon a rod 143 which extends through the recorder. At its opposite end the rod 143 carries a rigid arm 117 which corresponds to the lower arm of the bell-crank lever 115. These arms are each connected by links 118 to a rod 119, which extends into a slot 120 in a lever 121 which is loosely mounted upon the shaft 122. The end 123 of the lever 121 carries a pawl 124 which operates upon the ratchet 125. The ratchet 125 is rigid with a drum 126 mounted on shaft 122 which is adapted to receive a strip of paper 127 as it is unwound from the roll 128. When the cash drawer is pushed inwardly so that the bell-crank lever 115 through engagement with the lug 116 will be rocked upon its pivot the lever 121 will also be rocked upon its pivot 122 as it is connected with the bell-crank lever 115 by the links 118, the lever 121 causing the pawl 124 to feed the ratchet 125 forwardly so that a certain amount of paper will be unwound from the roll 128.

onto the drum 126. 129 is merely the usual retaining pawl. The paper travels over a platform 130 which serves as a writing support. The platform 130 is covered by a 5 glass plate 131 secured to the cover of the device. The glass 131 is cut away at 132 to allow sufficient space for one writing line. The glass is wide enough so that the last two or three previous records may always be 10 seen.

The rod 119 which extends across the roll 126 is furnished with a pair of sleeves 133 which bear against the paper as it is being wound upon the roll 126 and aid the paper 15 to be tightly and evenly wound upon the roll. The links 118 which carry the rod 119 will be rocked backwardly upon their pivots 134 as the size of the roll 126 increases and the lever 121 will rock a correspondingly 20 less distance to compensate for the increase in diameter of the roll so that the feed of the paper will be equalized. The spring 135 insures the proper pressure between the rod 119 and the roll of paper. The guides 144 25 also prevent the paper from being wound unevenly. When the paper is entirely wound upon the roll 126 and it is desired to insert a new roll of paper, the recorder is removed from the cash drawer and the sliding plates 30 136 are lowered out of engagement with the shaft 137. The roll 128 with the shaft 137 may then be removed. The arm 139 which is pivoted to the frame at 140 is now swung rearwardly so that its edge 141 will engage 35 pins extending from the pawls 124 and 129 and rock the pawls out of engagement with the ratchet 125. The paper may now be un wound from the roll 126 without interference from the pawls 124 and 129. The shaft 40 137 is withdrawn from the roll 128 and a new roll of paper inserted upon the shaft. The shaft is then dropped into the slot 142 the plates 136 springing upwardly and holding the shaft in its proper position. The 45 paper is then fed over the platform 130 and secured to the roll 126 by being inserted into a slot in the roll.

The mounting of the autographic device in the cash drawer is of particular value to 50 the proprietor in that the construction affords an additional check on the operator of the machine. It will be readily seen that the operation of the feeding means of the manual recorder mechanism is dependent 55 upon an operation of the accounting and printing mechanisms. By this construction the operator can only have access to the manual recorder by making some sort of record in the machine. An operation of the 60 machine will cause a feeding of the record strip in the drawer when the drawer comes open. The feeding mechanisms of the printing mechanism and the manual recorder may be timed so that the record strips of both 65 will be fed an equal distance at each opera-

tion of the machine. The proprietor may then lay the two strips side by side and by comparison of the two he can ascertain just what each item on the strip of the printing mechanism represents. If the operator fails to make an entry on the drawer strip the blank space will disclose this fact. If he fails to close the drawer each time, no feeding of the drawer strip will take place upon a subsequent operation and a comparison of the items on the two strips will disclose the fact that the drawer has been left open.

The automatic feed of the paper strip may be prevented by the removal of the lug 116. In this case the operator would himself rock 80 the bell crank 115 at such times as he wished to make a record on the strip.

While the form of mechanism herein shown and described is admirably adapted to fulfil the objects primarily stated it is to 85 be understood that it is not intended to confine the invention to the one form of embodiment herein disclosed, for it is susceptible of embodiment in various forms all coming within the scope of the claims which 90 follow.

What is claimed is as follows:

1. In an accounting machine, the combination with two similarly mounted members, of two linked arms pivoted respectively to said members, manually actuated means for differentially adjusting one of said members, means for acting on the point of linkage of said arms and thereby differentially positioning the other of said members, and an accounting device controlled as to operation by said other member.

2. In an accounting machine, the combination with a controlling plate, of manually actuated means for adjusting said plate comprising two links pivoted together and respectively to the actuating and the controlling plate to any of a plurality of positions, an actuating device, yielding connections from said actuating device to said controlling plate, means for adjusting said actuating device, through operation of said connections, and accounting devices controlled by said actuating device.

3. In an accounting machine, the combination with two similarly mounted members, of toggle arms connecting said members, manually actuated means for differentially adjusting one of said members, thereby changing the angle between said toggle arms, means for straightening said toggle arms and thereby differentially positioning the other member, and an accounting device controlled as to operation by said other member.

4. In an accounting machine, the combination with accounting devices of an actuator for the same, an adjustable stop, intermediate mechanism acting between the stop and the actuator so that the intermediate

- mechanism will cause the actuating mechanism to assume a certain relative position to that of the adjustable stop, and means for actuating the intermediate mechanism.
5. In an accounting machine, the combination with accounting devices of an actuator for the same, driving mechanism, an adjustable element for differentially communicating motion from the driving mechanism to the actuator, and means for adjusting said element independent of the actuator.
6. In an accounting machine, the combination with accounting devices of an actuator for the same, driving mechanism which is unvaryingly operated at each complete operation of the machine, an adjustable stop, intermediate mechanism acting between the stop and the actuator, the driving mechanism acting upon the intermediate mechanism so that the intermediate mechanism will cause the actuating mechanism to assume a certain relative position to that of the adjustable stop.
7. In an accounting machine, the combination with a totalizer of an actuator for the same, a manually shiftable device, a pair of links joining the shiftable device with the actuator, means for preventing movement of the actuator while the shiftable device is being moved, means for then locking the shiftable device in its moved position and unlocking the actuator, and means for then returning the joint between the links an amount which corresponds to its first movement for the purpose of positioning the actuator accordingly.
8. In an accounting machine, the combination with a totalizer of an actuator for the same, a manually shiftable device, a pair of links joining the shiftable device with the actuator, means for preventing movement of the actuator when the shiftable device is being moved, means for then locking the shiftable device in its moved position and unlocking the actuator, means for then returning the joint between the links to a definite position and so moving the actuator according to the movement of the shiftable device.
9. In an accounting machine, the combination with accounting devices of an actuator for the same, a pivoted adjustable element, a pivoted link connecting the adjustable element with the actuator, the adjustable element being free to rock upon its pivot without affecting the position of the actuator, separate means for then causing the link to move the actuator according to the extent to which the adjustable element had been moved.
10. In an accounting machine, the combination with a plate and an actuating device coaxially pivoted, of two links pivoted respectively to said plate and said actuating device, and pivoted together, means for differentially adjusting said plate, means for acting on the pivotal connection of said links and thereby adjusting said actuating device, and an accounting device controlled as to operation by said actuating device.
11. In an accounting machine, the combination with two members coaxially pivoted, of two linked arms pivoted respectively to said members, manually actuated means for differentially adjusting one of said members, means for acting on the point of linkage of said arms and thereby differentially positioning the other of said members and an accounting device controlled as to operation by said other member.
12. In an accounting machine, the combination with accounting devices of an actuator for the same, a driving member for the actuator, a manipulative device for adjusting the driving member independent of the actuator, and means for subsequently camming the driving member an extent determined by its adjustment so that the actuator and totalizer will be actuated accordingly.
13. In an accounting machine, the combination with accounting devices of means for actuating the same, a bank of keys for controlling the actuating means, a key detent for holding a depressed key in its depressed position, a rocking frame for returning the actuating means to zero position, and a cam carried by said frame and which operates the detent so that it will release a depressed key.
14. In an accounting machine, the combination with a totalizer, of a movable actuator therefor adapted to be differentially positioned as a preliminary to an actuation of the totalizer to predetermine the amount to be added on the totalizer, a series of keys, means under control of the keys for moving the actuator directly from one position to the other, and means for operating the totalizer whereby it will be actuated to an extent appropriate to the position of the actuator.
15. In an accounting machine, the combination with a totalizer, of a movable actuator therefor adapted to be differentially positioned as a preliminary to an actuation of the totalizer to predetermine the amount to be added on the totalizer, a series of keys and means under control of the keys for moving the actuator directly from one position to another.
16. In an accounting machine, the combination with a totalizer, an actuator therefor movable to different controlling positions, a series of keys and means under control of the keys for moving the actuator directly from one position to another.
17. In an accounting machine, the combination with a totalizer, of a differentially movable actuator therefor, a series of keys,

and means under the control of the keys for moving the actuator directly from one position to another.

18. In an accounting machine, the combination with a totalizer, of a differentially movable actuator therefor, a series of keys, means under the control of the keys for moving the actuator directly from one position to another, and mechanism for moving the totalizer over the actuator after the latter has been positioned to be actuated thereby.

19. In an accounting machine, the combination with a series of keys, an element differentially adjusted thereby, an actuator, means for moving the latter directly from one position to another under the control of the differentially movable element, a totalizer, and mechanism for moving the totalizer over the actuator to be actuated thereby.

20. In an accounting machine, the combination with a pair of differentially movable elements, of a toggle connection between said elements, means for adjusting one of said elements independently of the other thereby varying the angle of the toggle connection, and means for latching the said element in its adjusted position and for then readjusting the toggle connection to a constant angle, thereby differentially positioning the other movable element.

21. In an accounting machine, the combination with a pair of differentially movable elements, of a toggle connection between said elements, means for adjusting one of said elements independently of the other, thereby varying the angle of the toggle connection, devices for latching said element in its adjusted position, and means for readjusting the toggle connection to a constant angle after the adjusted element has been latched thereby differentially positioning the other movable element, and then restoring the first mentioned element to normal position.

22. In an accounting machine, the combination of a totalizer, an actuator therefor movable in either direction in any accounting operation as a preliminary to an actuation of the totalizer, and a series of keys for controlling the adjustment of the actuator whereby the totalizer is actuated from its actuator extents according to the key depressed.

23. In an accounting machine, the combination with a totalizer, of an oscillating actuator therefor movable in either direction in an accounting operation as a preliminary to an actuation of the totalizer, a series of keys and means under control of the keys for moving the actuator directly from one position to another.

24. In an accounting machine, the combination with a totalizer, an actuator therefor

movable to different controlling positions as a preliminary to an actuation of the totalizer, a series of keys, means under control of the keys for moving the actuator directly from one position to another, and means for operating the totalizer whereby it will be actuated to an extent appropriate to the position of the actuator.

25. In an accounting machine, the combination with a totalizer, of a differentially movable actuator therefor adapted to be moved differentially as a preliminary to an actuation of the totalizer, a series of keys, means under control of the keys for moving the actuator directly from one position to another, and means for operating the totalizer whereby it will be actuated to an extent appropriate to the position of the actuator.

26. In an accounting machine, the combination with a totalizer, an actuator therefor movable in either direction in an accounting operation as a preliminary to an actuation of the totalizer, a series of keys for controlling the adjustment of the actuator whereby the totalizer is actuated from its actuator extents according to the key depressed, and means for operating said totalizer whereby the same will be actuated according to the adjustment of the actuators.

27. In an accounting machine, the combination with a totalizer, of an oscillating actuator therefor movable in either direction in an accounting operation as a preliminary to an actuation of the totalizer, a series of keys, means under control of the keys for moving the actuator directly from one position to another, and means for operating said totalizer whereby the same will be actuated to an extent appropriate to the position of the actuator.

28. In an accounting machine, the combination with a totalizer, an actuator therefor movable to different controlling positions as a preliminary to an actuation of the totalizer, a series of keys and means under control of the keys for moving the actuator directly from one position to another.

29. In an accounting machine, the combination with a totalizer, of a differentially movable actuator therefor adapted to be differentially moved as a preliminary to an actuation of the totalizer, a series of keys, and means under the control of the keys for moving the actuator directly from one position to another.

In testimony whereof I affix my signature in the presence of two witnesses.

Corrections in Letters Patent No. 1,134,183.

It is hereby certified that in Letters Patent No. 1,134,183, granted April 6, 1915, upon the application of Edmund S. Church, of Dayton, Ohio, for an improvement in "Cash-Registers," errors appear in the printed specification requiring correction as follows: Page 6, lines 106-8, strike out the words "comprising two links pivoted together and respectively to the actuating and the controlling plate"; same page, line 111, after the word "plate" insert the words *comprising two links pivoted together and respectively to the actuating and the controlling plate*; and that the said Letters Patent should be read with these corrections therein that the same may conform to the record of the case in the Patent Office.

Signed and sealed this 18th day of May, A. D., 1915.

[SEAL.]

R. F. WHITEHEAD,

Acting Commissioner of Patents.
